Primary Examiner — John Windmuller*Assistant Examiner* — John R Yeh(74) *Attorney, Agent, or Firm* — Leason Ellis LLP(57) **CLAIM**

The ornamental design for a broom head, as shown and described.

DESCRIPTION

FIG. 1 is a top and front perspective view of a broom head showing our new design;

FIG. 2 is a front elevation view thereof, where the rear elevation view is a mirror image;

FIG. 3 is a top plan view thereof;

FIG. 4 is a bottom plan view thereof;

FIG. 5 is a right side elevation view thereof; and,

FIG. 6 is a left side elevation view thereof.

The broken lines shown in FIGS. 1-6 represent unclaimed subject matter (bristle area) and form no part of the claimed design.

1 Claim, 4 Drawing Sheets(56)
